UNITED STATES PATENT OFFICE.

WILLIAM N. STEVENSON, OF SOUTH ORANGE, NEW JERSEY.

SELF-CLOSING UMBRELLA.

SPECIFICATION forming part of Letters Patent No. 607,141, dated July 12, 1898.

Application filed December 31, 1897. Serial No. 665,141. (No model.)

To all whom it may concern:

Be it known that I, WILLIAM N. STEVENSON, a citizen of the United States, residing at South Orange, Essex county, New Jersey, 5 have invented certain new and useful Improvements in Self-Closing Umbrellas, of which the following is a full, clear, and exact description.

My invention relates to improvements in 10 self-closing umbrellas, and has for its object the provision of a simple, inexpensive, and effective means whereby the closing of the umbrella is mechanically effected, the locking means being released by the hand 15 which grasps the handle, thus doing away with the necessity of using two hands in accomplishing this end.

My invention is illustrated by the accompanying drawings, in which—
20 Figure 1 is a sectional view showing in perspective the inside of the umbrella cover and frame and particularly the construction of the latter. Fig. 2 is an enlarged detailed view.

25 A is a rod having a suitable handle at its free or lower end. Near its upper end and pivotally connected in the usual manner to said rod are ribs B B.

D is a runner of ordinary construction 30 adapted to slide on the rod A.

E E are stretchers. One end of each of said stretchers is pivotally connected to a notch carried by the runner D, while the opposite ends are pivotally connected to the 35 ribs B, preferably between a pair of lugs B' B'. The stretchers E perform the function of levers, their long ends being connected to the runner at notch D, while their short ends E', Fig. 2, project beyond the point where the 40 same is pivoted to the rib D, the pivotal connection with said rib forming the fulcrum for each lever.

F is a suitable spring. One end of each spring is anchored at B' to the rib. The opposite end of each of said springs is connected 45 to the short arm E' of the combined lever-stretcher E.

G is a detent in the rod A, which normally

projects into the return path of the runner D when the umbrella is opened, as in Fig. 1. 50 The retraction of the detent G causes it to move out of the path of said runner to allow the umbrella-frame to close. This detent is operated by a thimble H, preferably located adjacent the handle on the rod, a suitable 55 connection between the thimble H and the detent G being provided, as indicated in dotted lines.

I am aware that spring-actuated detents and means for controlling the position of same 60 are old, one means being shown in my earlier patent, No. 580,917, of April 20, 1897, and therefore I desire to have it understood that any suitable means may be provided in place of that specifically shown. 65

The invention herein relates particularly to the means for closing the umbrella, and without departing from the spirit of my invention it is manifest that the form of spring may be suitably modified. The means shown, 70 however, are simple in nature and permit the umbrella when closed to roll into very compact form, the size of the springs in actual practice being only approximately such as shown in Fig. 2. By the use of what is known 75 as the "octagon" frame—that is, a frame having corrugated ribs B—and by placing the springs F adjacent said corrugation the latter are at all times very largely sheathed within said corrugation, so as to be inconspicuous, and, as above stated, permitting the snug and compact folding of the umbrella when not in use. 80

Operation: Assume the parts to be in the position indicated in the drawings. To close 85 the umbrella, it is simply necessary to retract the detent G by means of the thimble H, at which instant the runner is forced downwardly on the rod A by the action of the springs E upon the combined lever-stretcher 90 arms, this being effected by the springs F, which when the parts are in the position indicated in Fig. 1 are under tension. As the runner D travels downward the ribs B move toward each other until they lie folded snugly 95 against the rod A.

What I claim is—

In a device of the character described, in combination, a channeled rib having lugs integral therewith, a stretcher pivoted between 5 said lugs and having a short arm adapted to move within said channel, a spring also in part within said channel and attached at one end to said rib and directly at the other end

to the end of said arm to automatically close said rib when released.

Signed at New York this 13th day of December, 1897.

WILLIAM N. STEVENSON.
